PULL ROD CARRIER

Allen M. Rossman, Wilmette, Ill.

Application March 10, 1941, Serial No. 382,474

15 Claims. (Cl. 74—522.5)

This invention relates to pull rod carriers, and more particularly to carriers of the type shown in my pending application, Serial No. 272,865.

In certain oil well districts horizontally reciprocating pull rods are used for transmitting power from a central engine or power to each of a plurality of pumps, some of which may be thousands of feet distant from the power. Each pull rod which extends from the power to a pump is supported by carriers every twenty-five or so feet in order to prevent excessive sagging of the pull rod or to prevent dragging on the ground.

The pull rod carrier of the type with which the present invention relates comprises a linkage pivoted about two stationary pivots and having one point thereof which moves in substantially a straight horizontal line. A pull rod support is mounted on the carrier at the straight line motion point thereof, and the pull rod rests upon that support. As the pull rod reciprocates it causes the pull rod carrier to swing with it, and the carrier supports the rod and guides it in substantially a straight line.

The carrier of the present invention comprises a so called Roberts straight line mechanism modified in certain respects to adapt it to the use to which it is to be put and to reduce the cost of construction and maintenance thereof. The Roberts type of straight line operating mechanism comprises a pair of equal arms or links pivoted at one end about spaced parallel axes and interconnected at their opposite ends by a third link. A point on the perpendicular bisector of the third link moves in a straight line. This point is utilized to support the pull rod.

In my application Serial No. 272,865, above referred to, the arms are made of considerable length so that the straight line motion point of the mechanism will lie above the stationary pivots of the arms. In this type of Roberts mechanism, when the pull rod reaches one extreme position, all of the weight on the carrier is imposed upon one of the arms and, in addition, that one arm exerts a tension on the other arm. Each arm is thus under compression during the major portion of the stroke and under tension at one end of the stroke. As a result the wear on the bearings is at the top and at the bottom of the bearing. After there has been some wear in the bearings play develops due to back lash as the stress on a link or arm goes from compression to tension. It is one of the objects of the present invention to overcome this difficulty by using a Roberts type of mechanism which is so proportioned that the supporting arms are always in compression and

never in tension. The wear on the bearings is therefore always in the same direction and can thus be readily taken up after considerable wear has occurred. Also, even before the wear is taken up there will be no back lash as the carrier oscillates from its center position to either extreme position, since the direction of the stress in each link remains the same throughout the cycle of movement of the pull rod.

10 It is a further object of the present invention to provide a pull rod carrier of the above mentioned character with a simple type of bearing support which will allow a quick assembly of the carrier in the field. It is a still further object of the present invention to provide an improved carrier of the above mentioned character wherein the arms are comparatively short thus reducing the amount of material required for the carrier and also reducing the momentum of the moving parts by reducing their mass.

15 It is a still further object of the present invention to provide an improved carrier of the above mentioned character wherein the carrier supporting base acts as a stop to limit the motion 20 of the carrier in each direction without the addition of material to the base for accomplishing the stopping function.

The attainment of the above and further objects of the present invention will be apparent 25 from the following specification taken in conjunction with the accompanying drawing forming a part thereof.

In the drawing:

Figure 1 is a plan view of a carrier embodying 30 the present invention;

Figure 2 is a front view of the carrier of Figure 1;

Figure 3 is an end view thereof;

Figure 4 is a fragmentary perspective view of 40 the lower end of one of the supporting arms of the carrier of Figure 1; and

Figure 5 is a perspective disassembled view of the pull rod support of the carrier of Figure 1.

Reference may now be had more particularly 45 to the drawing, wherein like reference numerals designate like parts throughout. A pull rod carrier which is indicated at 1 supports a pull rod 2 that reciprocates horizontally. The pull rod 2 is one of a number of pull rods each extending 50 from a source of power to different pumps in an oil field. Some pumps are comparatively close to the power and others may be thousands of feet away. The pull rod 2 is supported at regular intervals, approximately twenty-five feet apart, by carriers such as the carrier 1. The carrier is

mounted on a post or foundation 4 which is rigidly anchored in the ground as, for instance, by being set in concrete. The post 4 may comprise a circular steel pipe. At a suitable distance above the ground the post 4 has a carrier supporting assembly 5 secured thereto. This assembly may comprise a short length of pipe 6 cut out at its periphery so that it can fit around the post 4, as indicated at 7, and having aligned holes therethrough for receiving the shanks of a U-bolt 8. A steel supporting rod 9 is welded to the pipe 6. A short second rod 10 is also welded to the pipe 6. The U-bolt 8 embraces the post 4 and extends through the holes in the pipe 6 and is secured in place by nuts 11 threaded on the U-bolt and bearing against the rods 9 and 10. The U-bolt thus firmly secures the supporting rod 9 to the post 4. The supporting rod 9 is bent at its opposite ends to form arms 12-13 constituting pivot rods or bearing supports. A pair of spaced washers 14-15 are spot welded to each bent portion of the supporting rod 9. The space between each set of washers 14-15 constitutes a bearing support.

Arms or links 17-18 of a straight line operating mechanism are each supported by the bent portions of the supporting rod between the washers 14-15. The arms or links 17 and 18 are of identical size and construction. Each arm comprises two wooden boards 20-21 secured together in spaced relationship by rectangular bearing blocks. The upper bearing block, indicated at 22, is merely an oil soaked hard wood block having a longitudinally extending hole therethrough which forms a bearing. The upper bearing block is bolted to the boards 20-21 by two bolts 24 that extend through the boards and through the bearing block 22. The lower bearing block, indicated at 26, comprises an oil soaked hard wood block having a longitudinal slot 27 therein, the top of which slot terminates in a smooth circular curve 28. The lower bearing block is secured between the arms 20-21 by two bolts 30 that pass through the boards 20-21 and through the arms 31-31 of the bearing block 26.

A Z-shaped link 35 pivotally connects the arms 17-18. This link comprises a steel rod bent to Z-shape so that it has parallel arms 36-37 joined by the diagonal portion 38 of the Z. Washers 40-41 are spot welded to the arms 36-37 respectively. The Z-shaped link includes a depending rod 42 welded to the portion 38 at the center thereof. The rod 42 is at a slight inclination to a vertical plane determined by the longitudinal axis of the pull rod 2, as may be seen from Figure 3. At its lower end the rod 42 has a short steel rod or stem 43 welded thereto and extending horizontally therefrom. The stem 43 has a pair of spaced washers 44-45 mounted thereon and spot welded thereto. A slotted oil soaked hard wood block 46 is slipped over the stem 43 between the washers 44-45 and is secured in place by a bolt 47. The slot in the block 46 terminates at its top in a smooth circular curve 48 which rests on the stem 43 and turns thereon. A metal strap 49 depends from the bolt 47 of the block 46. The pull rod 2 rests upon that strap and may be readily removed therefrom merely by lifting the pull rod 2 upwardly.

To assemble the pull rod carrier the link 17 is strung on the arm 36, said arm passing through the bearing hole in the block 22 of the arm 17 until that block 22 abuts against the washer 40. In the same manner the link 18 is mounted on the arm 37 by passing the arm 37 through the

corresponding hole in the corresponding block 22 of the link 18 until that link abuts against the washer 41. The lower ends of the links 17 and 18 are then slipped down upon the arms 12 and 13, respectively, between the washers 14 and 15 so that the slots 27 of the blocks 26 embrace the arms 12 and 13 and with the curved surfaces 28 of the two blocks resting on the arms 12 and 13. The blocks 26 are then secured against upward removal by the bolts 30. The Z-shaped link 35 is now held against movement in one direction by the washer 40 which engages one side of the link 17 and by the corresponding washer 41 which engages the opposite side of the link 18. The strap 49 may then be positioned on the bolt 47. Thereafter the pull rod 2 may be positioned upon the strap 49.

It may be seen that the carrier I comprises a four link chain the links of which are pivoted together to form a quadrilateral, as illustrated in Figure 1. The supporting rod 9 constitutes one link between the pivot axes 12-13. The arms 17-18 constitute two other links and the arm 35 between the pivot axes 36-37 constitutes the fourth link. In order to obtain the requisite motion for the center 50, within the limits of the to and fro movement of the carrier, it is essential that the link lengths be of certain proportions with respect to one another. In dealing with these proportions the lengths or distances considered are the center to center distances between the respective pivots.

The proportion of the linkage is such that the path of movement of the center 50 of the stem 43 is substantially a straight line within the limits of motion of the pull rod 2. A suitable linkage for obtaining this result with a pull rod having a stroke of 42 inches is of the following proportions: distance between the centers of the arms 12-13, 34 inches; lengths of links 17-18 from center to center of the arms 12-36 and 13-37, 13 inches; center to center distance of the arms 36-37, 22 inches; center to center distance between the stem 43 and the center of the Z-shaped link 35, 30 inches.

It is to be noted that the axis of the pull rod 2, as seen in Figure 3, is vertically centered with respect to the links 17-18 and the Z-shaped link 35. This eliminates uneven stresses on the bearings tending to twist the links.

As the pull rod moves to the right of the position illustrated in Figure 2 it draws the pull rod carrier with it from the full line position to an extreme position illustrated by the dash lines of Figure 2. At that extreme position the arm 36 abuts against the supporting rod 9 and limits the extent of motion of the carrier. Any additional movement of the pull rod 2 to the right, after the carrier reaches its limiting position, results merely in slipping or sliding of the pull rod on the support 49. When the pull rod commences to move in the opposite direction it draws the carrier with it from the dash position illustrated, to its center full line position and onward to a position approximately corresponding to the dash position illustrated but on the opposite side of the center. The carrier is proportioned so that the length of the stroke of the center point 50 in opposite directions, as limited by abutment of the arm 36 or the arm 37 against the rod 9, is slightly in excess of the maximum stroke of the pull rod 2. Therefore, if the pull rod is removed from the carrier while the carrier is in any position, and replaced on the carrier after the carrier has moved to another position, then

during the first stroke of the pull rod it will draw the carrier to one extreme position or the other thereof and then slide on the carrier until the pull rod is again centered on the carrier. Thereafter, during operation of the pull rod there will be no further sliding of the pull rod in the strap 49.

When the carrier is in its mid position the entire weight of the pull rod is carried by the links 17-18 both of which are in compression. This continues even until the carrier reaches its limiting position for even in its extreme position, illustrated in dash lines of Figure 2, the link 18 is still on the same side of a vertical plane passing through the pivot axis 13. The link 18 never passes through a vertical position. Therefore, even in its extreme position the force on the link 17 due to the weight of the pull rod is still in compression. As a result the bearing blocks 22 and 26 wear only at one surface, which would not be the case if the link were placed in alternate compression and tension as the carrier moves through its cycle. This permits a simple construction of the blocks 26. Furthermore, since the blocks are always in compression any wear on the bearings will not result in back lash as the pull rod carrier moves from one extreme position to the other. From the above it is apparent that the proportioning of the links of the straight line operating mechanism is so correlated to the length of the stroke of the pull rod that the stopping action of the carrier is obtained before either arm 17 or 18 passes through its vertical position. Wear on the bearings 22-26 merely results in a slight foreshortening of the effective lengths of the links 17-18. This is of such small magnitude as to produce a negligible effect in the straight line travel of the center 50. This is possible because the links 17-18 are always in compression during the movement of the carrier from one extreme position to the other. If the links were in tension during part of the stroke then wear on the bearings could not be tolerated for, under such circumstances the carrier would knock during each cycle as the stress on the link passes from compression to tension and the link moves in its bearing because of the wear. By providing a structure wherein the stress on each link is always in the same direction, wear on the bearings cannot produce back lash during the operation of the carrier.

While I have shown the pull rod supported from the block 46 by means of the strap 49, this is not an indispensable part of the invention. For instance, the pull rod may rest on the top of the block 46, if desired. Under such circumstances the top of the block would be provided with a V-shaped groove for receiving the pull rod and holding it against side movement across the block, in the manner illustrated in my pending application, Serial No. 272,865.

In compliance with the requirements of the patent statutes I have here shown and described a preferred embodiment of my invention. It is, however, to be understood that the invention is not limited to the precise construction here shown, the same being merely illustrative of the principles of the invention. What I consider new and desire to secure by Letters Patent is:

1. A pull rod carrier comprising a base, a cross member pivotally supported at each end by arms of equal length which are pivotally attached to said base, said cross member having a part which is rigidly fixed to the rest of the cross member and depends from a line joining the pivots at the

ends of the cross member, a pull rod support pivoted at a lower point of said depending part which is an equal distance from the pivots and is adapted to reciprocate in a substantially straight line motion, said cross member abutting against the base as the cross member pivots a fixed distance in either direction from its mid position to stop the reciprocating motion of said support at fixed points.

2. Apparatus of the character described comprising a base member, inclined converging arms pivotally supported at one end in spaced relation by said base member, a member pivotally supported between the opposite ends of the arms, a support affixed to said pivotally supported member and located an equal distance from both pivotal supports of the pivotally supported member and at a distance from the said pivots of the last member greater than the distance between those pivots, and adapted to reciprocate in a substantially straight line, and substantially below the base member, the distances between the pivots being such that the direction of swinging movement of either arm is reversed as it approaches a vertical position and before it pivots through its vertical position, and means for positively stopping the motion of said pivotally supported member at fixed points.

3. A pull rod carrier comprising a base, a cross member pivotally supported at each end by arm members of equal length which are pivotally attached to said base, said cross member having a part which is rigidly fixed to the rest of the cross member and depends to a level substantially below the base, a pull rod support pivoted at a lower point of said part which point is an equal distance from both pivots and is adapted to reciprocate in a substantially straight line motion, at least one of said members abutting against the base to stop the reciprocating motion of said support at a fixed point.

4. Apparatus of the character described comprising a base member, arms pivotally supported at one end in spaced relation by said base member, a cross member pivotally supported between the opposite ends of the arms, a support affixed to said cross member and located an equal distance from both pivotal supports of the cross member and at a distance from the said pivots of the last member greater than the distance between those pivots, and adapted to reciprocate in a substantially straight line, said cross member moving into abutment with the base at a point adjacent the pivot between the cross member and at least one of the arms for positively stopping the motion of said support at fixed points.

5. Apparatus of the character described comprising a base member, upstanding arms pivotally supported in spaced relation by said base member, a depending member pivotally supported intermediate the upper ends of said arms and depending below the base member, a support affixed to said depending member below the base member adapted to reciprocate in a substantially straight line, a portion of the depending member that is adjacent the pivot between it and each arm abutting the base member as the arms pivot, for positively stopping the motion of said support at fixed points.

6. In combination with a horizontal longitudinally reciprocating pull rod, a pull rod carrier supporting the rod and comprising a straight line operating mechanism pivoted about two spaced parallel horizontal axes above the pull rod and at right angles thereto and a distance apart less than

the stroke of the rod, and a pull rod support pivoted on the carrier at a straight line motion point thereof below said parallel axes, said pull rod resting on said support.

7. A straight line operating mechanism comprising a support, a pair of equal arms pivoted on the support and extending upwardly therefrom, a link pivotally connecting the upper ends of the arms and having a depending portion extending below the support and having a point thereof below the support movable in a straight line, said link being movable into a position in abutment with the support as the straight line mechanism operates, thereby limiting the stroke of the mechanism.

8. A straight line operating mechanism comprising a support, a pair of equal length upstanding arms pivoted on said support, and a Z-shaped cross member pivotally connecting and supported by the arms, said cross member overlying the support and being moved into abutment with the support as the arms pivot in either direction from a mid position, to limit the movement of the mechanism in each direction from the mid position.

9. A straight line operating mechanism comprising a support having spaced parallel horizontal stationary pivot rods, a pair of arms of equal lengths each of which has a bearing block at its lower end, the bearing blocks being slotted with the slotted portion of each block embracing a rod and resting thereon whereby the arms are pivoted on the rods, a cross member pivotally connecting the upper ends of the arms and having a depending portion a point of which is located an equal distance from the pivotal connections between the arms and the cross member.

10. A linkage comprising a Z-shaped cross member having parallel arms joined by a diagonal member, a pair of equal links having bearing blocks at one end, the arms of the cross member extending each through one of the bearing blocks, stop means on each of the arms between the diagonal member and the bearing block for limiting the extent of insertion of the arms into the bearing blocks, means pivotally supporting the opposite ends of the links, and means at said opposite ends for restraining the links from movement in a direction longitudinally of said arms.

11. A linkage comprising a Z-shaped cross member having parallel arms joined by a diagonal member, a pair of equal links having bearing blocks at one end, the arms of the cross member extending each through one of the bearing blocks, stop means on each of the arms between the diagonal member and the bearing block for limiting the extent of insertion of the arms into the bearing blocks, the bearing blocks being slidable along the arms in a direction away from the diagonal member and the stop means, means pivotally supporting the opposite ends of the links, and means at said opposite ends for restraining the links from movement in a direction longitudinally of said arms, the pivot supporting means for the said opposite ends of the links comprising slotted bearing blocks, and stationary bearing shanks embraced by the slotted portion of said slotted blocks and supporting said blocks.

12. In combination with a horizontal longitudinally reciprocating pull rod, a pull rod carrier supporting the rod and comprising a straight line operating mechanism having a pair of equal arms pivoted about spaced stationary axes, a cross member pivotally joining the arms to swing about two movable axes, a pull rod support carried by the cross member at a point which is an equal distance from the two movable axes, the length of an arm plus the distance between the movable axes being less than the hypotenuse of a right triangle of which one arm and the distance between the stationary axes constitute the other two sides, whereby the direction of swing of either arm is reversed as the arm approaches a vertical position and before it pivots through a vertical position, the distance between the fixed axes being less than the stroke of the rod.

13. A straight line mechanism comprising a four link chain pivoted together to constitute a quadrilateral, said chain including two opposite links of equal effective lengths and two of unequal lengths, the smaller of the two unequal links overlying the other of the two unequal links and being moved into abutment therewith as the equal links pivot in either direction from a mid position, to limit the actuation of the mechanism in each direction from the mid position.

14. A carrier comprising a four link chain pivoted together to constitute a quadrilateral, two of the links being of equal effective lengths and the other two of unequal lengths, supporting means comprising a pivot and means maintaining said pivot spaced a fixed distance from one of said unequal links and spaced substantially equidistant from the two pivots of said one of the unequal links, the longer of said two last mentioned links also constituting a supporting means, a support for the carrier at one of said supporting means, the other supporting means including means for supporting a horizontally reciprocating rod, the reciprocation of the rod actuating the linkage in a to and fro motion, a part of one of the links of the chain being moved into abutment with a part of another link of the chain at points slightly beyond the limits of the stroke of the rod to limit the actuation of the carrier.

15. A pull rod carrier for a reciprocating substantially horizontal pull rod of such length as to require support between its ends to prevent excessive sagging of the rod, said carrier comprising a pair of equal links, means holding the ends of the links a fixed distance apart and providing parallel pivot axes a fixed distance apart, a cross member pivotally joining the links, another pivot axis, means including the cross member for maintaining the pivots between the cross member and the links at fixed equal distances from said other pivot axis, said other pivot axis and the first mentioned pivot axes being relatively movable with respect to one another in a straight line under the guidance of the cross member and the said links, said cross member overlying and being moved into abutment with a part of the carrier as the links pivot in either direction from a mid position, to limit the actuation of the carrier in each direction from the mid position.

ALLEN M. ROSSMAN.
